GRIPPING DEVICE

William John Novak, Drumright, Okla., assignor
to M. S. Patton, Tulsa, Okla.

Application October 23, 1935, Serial No. 46,363

4 Claims. (Cl. 24—248)

This invention relates to a gripping device which is mainly designed for use with the rods, tubing, and cables of well apparatus, but which of course can be used for other purposes.

5 The general object of the invention is to provide a body carrying a number of gripping jaws and eccentric levers for moving the jaws into gripping relation when the levers are moved in one direction and means whereby a movement of 10 the object gripped by the jaws will open the jaws sufficiently to let the object move in one direction but movement in the opposite direction of the object will be prevented by the jaws being held in gripping position by the levers.

15 A further object of the invention is to provide a jack or the like, whereby the device can be moved to a position to cause the levers to release the jaws.

This invention also consists in certain other 20 features of construction and in the combination and arrangement of the several parts to be hereinafter fully described, illustrated in the accompanying drawings and specifically pointed out in the appended claims.

25 In describing the invention in detail, reference will be had to the accompanying drawings, wherein like characters denote like or corresponding parts throughout the several views, and in which:—

30 Figure 1 is a front view of the device showing the same held in raised position by a jack.

Figure 2 is an end view of Figure 1.

Figure 3 is a rear view of the device with the parts broken away.

35 Figure 4 is a top plan view with the jack removed.

Figure 5 is a perspective view of the body which carries the jaws and the levers.

Figure 6 is a perspective view of the base member and the slotted uprights which guide the body in its vertical movement.

In these drawings, the numerals 1 and 2 indicate a pair of elongated base plates having a pair of holes therein, one adjacent each end thereof 45 which receives a sub-shaft 3, pins 4 passing through holes adjacent the ends of the shafts for holding the parts together and these pins of the plate 2 may be connected to a part of the device by a chain 5 and this plate 2 has a handle 6 connected thereto, so that by removing the pins, the plate can be removed by a pull on the handle. Levers 7 have holes adjacent the inner ends 50 through which the sub-shafts 3 pass, the inner end of each lever forming a rounded eccentric 8, the outer portion of each lever extending well

beyond the end of the body formed of the two plates. A pair of gripping jaws 9 are removably located in the central portion of the space between the two plates, and each jaw has an outer arcuate recess 10 therein for receiving the rounded extremities 8 as more clearly shown in Figure 3. The inner edge of each jaw is formed with a substantially semi-circular groove 11, the two grooves providing the space for the object to be gripped such as a pipe, rod or other member, and as will be seen when the outer portion of the levers 7 are raised, the eccentric parts 8 will press the jaws together in gripping relation upon an object, but by swinging the levers downwardly the jaws can move apart out of gripping relation to 15 the object.

By moving the jaws toward each other so that the recesses 10 will disengage the eccentrics 8, the jaws can be lifted from the space between the two plates and in order to prevent mislaying of 20 the jaws, I prefer to attach them to one of the plates by the chains 12.

I also provide a base 13 which has a centrally arranged notch 14 therein for the passage of the object to be gripped and adjacent the inner end 25 of the notch, an upright 15 rises from the base, which is formed with a notch 16.

A vertically arranged member 17 is connected with the central part of the plate 1 and has the outwardly extending wings 18 at its lower 30 end, which forms spaces between themselves and the plate 1, which spaces act as guiding means with the parts of the upright 15 and said member 17 is provided with a reduced inner portion which passes through the slot 16. The upper part of the 35 member is provided with a hole 19 and an outstanding lip 20 which is connected with an intermediate part of the member. The base 13 is provided with a recess 21 for receiving the reduced lower end of an upright 22 of a jack A, said 40 upright 22 being formed with a shoulder 23 and the lever 24 of the jack has a reduced end 25 for entering the hole 19.

As will be seen the body of the device which carries the levers and jaws is supported for 45 vertical sliding movement by the upright of the base and the member 17. By use of the jack the said body can be lifted and held in lifted position, but when the jack is removed the body assumes a lower position, as shown in Figure 3, 50 under the action of gravity and when in lowered position the outer ends of the levers 7 will engage the ends of the base 13 so that the levers are swung to position where their eccentrics 8 will force the jaws into gripping relation upon a pump 55

rod B, a pipe or tube, or other object passing through the jaw.

Thus, with the parts in the position shown in Figure 3, the object B will be driven by the 5 jaws, so that it cannot move downwardly but an upward pull on the object will lift the body away from the base so that the levers 7 will swing downwardly and thus the jaws will be released so that the object can be moved upwardly 10 but it cannot be moved downwardly. By raising the body by the jack the object may be moved both downwardly and upwardly as the jaws will not grip the same.

It is thought from the foregoing description 15 that the advantages and novel features of the invention will be readily apparent.

It is to be understood that changes may be made in the construction and in the combination and arrangement of the several parts provided that such changes fall within the scope of 20 the appended claims.

Having thus described the invention what is claimed as new is:—

1. A gripping device of the class described comprising a body of hollow construction, a pair of levers pivoted to the end portions of the body adjacent their inner ends, with their outer ends projecting from the ends of the body, the inner ends of the levers forming eccentrics, a pair of 25 jaw members located in the body and having recessed portions engaged by the eccentric parts of the levers, whereby movement of the levers in one direction will move the jaw members into gripping relation with an object passing through the 30 same.

2. A gripping device of the class described comprising a hollow body, a pair of jaws therein having recesses in one side thereof, a pair of pivots passing through the body, one adjacent each end 35 thereof and between which the jaws are located, a lever supported by each pivot, adjacent the inner ends of the lever, said inner end of each member formed of eccentrics for engagement in the recess in a jaw, means for supporting the body for

limited movement, such means including means for causing the levers to move the jaws in gripping position when the body is moved in one direction and to release the jaws, when the body is moved in an opposite direction.

3. A gripping device of the class described comprising a hollow body, a pair of jaws therein having recesses in one side thereof, a pair of pivots passing through the body, one adjacent each end thereof and between which the jaws are located, a lever supported by each pivot, adjacent the inner ends of the lever, said inner end of each member formed of eccentrics for engagement in the recess in a jaw, means for supporting the body for limited movement, such means including means for causing the levers to move the jaws in gripping position when the body is moved in one direction and to release the jaws, when the body is moved in an opposite direction, and means for holding the body in position with the 20 jaws released when desired.

4. A gripping device of the class described comprising a pair of plates, sub-shafts passing through the plates one adjacent each end thereof, levers having eccentric inner ends and openings adjacent said inner ends through which the shafts pass, a pair of removable jaws fitting between the plates with their upper ends projecting therefrom, outer portions of the jaws having recesses for engagement by the eccentrics of the levers, 30 and each jaw having a smooth gripping surface, said eccentric being movable out of said recesses so that one plate can be removed to permit an object to be placed between the jaws, a base having a notched upright, the body having a projecting part provided in said upright, said projecting part having a lip thereon and jack means for engaging the part of the base and said lip for lifting the body to place the jaws in inoperative position, the levers engaging a part of the base when the 40 body is lowered to cause the eccentrics to move the jaws into gripping position.

WILLIAM JOHN NOVAK.
